Specification for Design.

Patented Oct. 28, 1913.

Application filed July 9, 1913. Serial No. 778,225. Term of patent 14 years.

To all whom it may concern:

Be it known that I, THOMAS MOUNTFORD, a citizen of the Dominion of Canada, residing at Newark, in the county of Essex and State of New Jersey, have invented a new, original, and ornamental Design for a Base for Gem-Settings, of which the following is a specification, reference being had to the accompanying drawing, forming part thereof.

Figure 1 shows a plan view of my design for a base for gem settings. Fig. 2 is a side view of Fig. 1.

I claim:

The ornamental design for a base for gem settings, as shown.

In testimony whereof I have signed this specification in the presence of two subscribing witnesses.

THOMAS MOUNTFORD.
